DESIGN FOR A PRACTICE GUN STAND

Nathen E. Squire, Chicago, Ill., assignor to Ford Amusement Devices, Inc., Chicago, Ill., a corporation of Illinois

Application June 26, 1936, Serial No. 63,512

Term of patent 3½ years

To all whom it may concern:

Be it known that I, Nathen E. Squire, a citizen of the United States, residing at Chicago, county of Cook, and State of Illinois, have invented a new, original, and ornamental Design for a Practice Gun Stand, of which the following is a specification, reference being had to the accompanying drawing forming part thereof, and in which:

Fig. 1 is a perspective view of the new practice gun stand showing a front, top, and side wall thereof, the said side walls being identical in appearance; and

Fig. 2 is a top plan view of the same.

I claim:

The ornamental design for a practice gun stand as shown and described.

NATHEN E. SQUIRE.
